(57) **CLAIM**

The ornamental design for an assembling toy, as shown and described.

DESCRIPTION

FIG. 1 is a front view of an assembling toy of the present invention in a first position.

FIG. 2 is a rear elevation view thereof.

FIG. 3 is a top plan view thereof.

FIG. 4 is a bottom plan view thereof.

FIG. 5 is a right-side elevation view thereof.

FIG. 6 is a left-side elevation view thereof.

FIG. 7 is a perspective view thereof.

FIG. 8 is a front elevation view in a moved position.

FIG. 9 is a sectional view thereof taken along section line 9-9 of FIG. 1; and,

FIG. 10 is a sectional view thereof taken along section line 10-10 of FIG. 3.

The broken lines depict portions of the article that form no part of the claimed design. The long and short dashed line arrows indicate the cross-section views, and form no part thereof.

1 Claim, 10 Drawing Sheets
